UNITED STATES PATENT OFFICE

EMIL RICHTER, OF WYOMISSING, PENNSYLVANIA, ASSIGNOR TO TEXTILE MACHINE WORKS, OF WYOMISSING, PENNSYLVANIA, A CORPORATION OF PENNSYLVANIA

MECHANISM FOR KNITTING FULL FASHIONED HOSIERY

Application filed October 31, 1930. Serial No. 492,495.

This invention relates to a novel improved means for knitting fashioned fabric such as full fashioned hosiery.

According to the present well known method of making the finer grades of full fashioned hosiery, the fashioning or narrowing of the fabric is effected by shifting or transferring the loops a distance of two needles. This has heretofore been considered necessary in order to produce a perfectly uniform selvage edge to facilitate subsequent seaming, and on account of the two needle thread carrier movements permits the tips thereof to be stopped between two sinkers and directly above a divider, of lesser height to accommodate the same. It has been found that this two needle transfer movement excessively stresses the yarn, thereby bending the narrowing points and needles and preventing them from registering properly, with consequent imperfect transfer and frequent dropping of the loops. Owing to the gummed condition of the silk these resultant defects do not always yield to the numerous tests and inspections given at various stages of stocking completion, and frequently runs are started when the stockings are subjected to stretching when worn for the first time.

The fashioning marks produced in the stocking by the two needle transfer method are also very conspicuous, which is objectionable.

The primary objects of my invention are, to provide improved means and a new method of producing full fashioned stockings in accordance with which the above detrimental conditions are eliminated; and thereby to produce a stocking of better quality and appearance.

In accordance with my invention, the fashioning loops are shifted a distance of one needle only, and in novel manner, thereby preventing the stressing of the yarn at the narrowing points and effecting perfect loop transference; also producing a stocking not

subject to defects at the points of narrowing, as above pointed out, and in which the fashioning marks are inconspicuous.

The above and other objects will become more readily apparent by referring to the following detailed description and accompanying drawings of an embodiment of the invention.

In the drawings:

Fig. 1 is a side view of a stocking made in accordance with my invention.

Fig. 2 is a fragmentary enlarged view of a part of a flat knitted stocking blank, and more particularly shows the manner in which the loops are transferred and the selvage edge produced, in carrying out my novel method.

Figs. 3, 4 and 5 are diagrammatic views showing the various positions of a thread carrier rod and the narrowing rods of a full fashioned knitting machine during one cycle of operation in carrying out my improved method of producing the stocking fabric shown in Fig. 2.

Fig. 6 is a top plan view of certain parts of a well known full fashioned stocking knitting machine having my improved mechanism applied thereto for carrying out my new method of producing the stocking of Fig. 1.

Fig. 7 is an end view of the mechanism shown in Fig. 6, looking in the direction of the arrow A in said figure.

In accordance with my new method of producing the full fashioned stocking shown in Fig. 1, the welt 10 is produced in the usual and well known manner on a full fashioned knitting machine. Knitting of the leg part 11 is then continued, as heretofore, except that in fashioning, the loops 12 transferred by the well known narrowing points (not shown) on the narrowing or fashioning rods are moved inwardly a distance of one needle only, at each edge of the fabric, instead of two as customary heretofore.

One way of accomplishing this, which I

- have found to be satisfactory in practice, will be apparent to those skilled in the art by referring to the diagrammatic illustrations of Figs. 3, 4 and 5, which indicate one cycle of operation of the well known parts of a full fashioned knitting machine instrumental in carrying out my improved method. In these figures, 14 indicates the ordinary thread carrier rod used in laying the yarn 10 to produce the fabric; 14a, 14b the spindle operated end stops for the rod 14; 15 and 16 the narrowing rods on which the usual narrowing points are mounted, and 15a, 15b, 16a, 16b the spindle operated end stops 15 against and between which the rods 15 and 16 are yieldingly held by springs, as shown. The spaces indicated by the dot-and-dash lines 0, 1, 2, at the ends of these figures are to be considered as representing distances 20 between successive needles.
- Starting with the position shown in Fig. 3, the narrowing rods 15 and 16 are simultaneously moved downwardly to engage the loops at a desired point of narrowing, are 25 then raised and the stops 15a, 15b, 16a, 16b, are moved inwardly a distance of one needle only, while simultaneously with this movement, stops 14a and 14b are moved inwardly a distance of two needles, as heretofore. The 30 respective parts are shown in the positions reached at the end of the movement just described in Fig. 4. The narrowing rods are now lowered to transfer the loops the shifted distance of one needle, after which the rods 35 are again raised. While the rods 15 and 16 are being raised, the stops 15a, 15b, 16a, 16b, are again moved inwardly a distance of one needle, thereby bringing these stops in the same relative position with respect to the 40 stops 14a and 14b as before, and placing all the stops in advanced position a distance of two needles, (see Fig. 5) in readiness for the next narrowing operation. This completes the cycle of operation.
- 45 By referring now to the loop formation of the fabric shown in Fig. 2, it will be noted that the fashioning or narrowing marks F produced by transferring the loops 12 inwardly a distance of one needle, are inconspicuous, and that a selvage edge is produced which can be readily seamed. A free loop d is alternately produced at opposite edges of the fabric in the line of loop transfer when the yarn carrier and loops being transferred 50 simultaneously move inwardly from the edge of the fabric. These free loops afford no difficulties in the later finishing of the stocking and can be readily secured by the seaming operation.
- 55 After completion of the leg part 11 of the stocking fabric the foot part 20 is added thereto as heretofore, and the flat fashioned blank obtained in this manner is seamed as usual, to complete the stocking.
- 60 It will be noted from Figs. 1 and 2, that

not only the fashioning marks F are inconspicuous in the stocking produced according to my invention, but that the courses beyond the fashioning marks F slope off at an angle that makes the variation hardly noticeable. 70

One form of novel mechanism which I have found in practice to satisfactorily operate the thread carrier rod stops and narrowing rod stops in accordance with the above described method, is shown in Figs. 75 6 and 7, which illustrate the mechanism at one end of the machine, and in which the same reference numerals have been applied corresponding with the parts shown in Figs. 3, 4 and 5. 80

This mechanism is similar to that employed for the two needle transfer movements mentioned, and differs therefrom only in that the pawling device for the narrowing rod spindle 26 is changed so as to carry out the one needle movement already described. This will be apparent by referring particularly to Fig. 7. 85

Numeral 17 indicates the usual cam on the machine cam shaft (not shown) that imparts movement through a rocker arm 18 to a vertically reciprocative member 19, which carries spring actuated pawls 21 and 22 that coact with ratchet wheels 23 and 24, respectively secured to the thread carrier rod spindle 25 and the narrowing rod spindle 26. Notched disks 27 and 28 are also secured to the spindle which cooperate with spring pressed stop plungers 29 and 31 to hold the spindles in position after being pawled. 90 95

In order to accomplish the successive one needle movements, one active and the other idle, to shift the narrowing rods 15, 16 as above described, disk 28 is provided with the proper number of notches on its periphery, the distance between successive notches representing a one needle movement of the stops 15a 15b; and the ratchet wheel 24 is provided with a like number of teeth. A second pawl 32 pivotally mounted on the member 19, cooperates with the ratchet wheel 24 at a point opposite to that of pawl 22, and is normally held in engagement with the wheel by a spring 30 secured thereto and to a horizontally movable arm 34. 100 105 110

The pawls 21 and 22 are provided with extensions 36 and 37 which are connected by a link 38 and the latter is slotted at 39 to afford a loose connection to permit independent movement of the pawl 22. A cam 41 is secured to a machine frame element 42, which engages and coacts with extension 37 to retain the pawl 22 in disengaged position when the element 19 is in its lowermost position and to prevent the pawl from falling into engagement with the ratchet wheel 24 during upward movement of element 19 until after one tooth has been passed. From this it will be apparent that when the element 19 is shifted upwardly to its full extent, pawl 115 120 125 130

22 will turn spindle 26 sufficiently to move stops 15a and 16a a distance of one needle. During such movement pawl 21 will turn spindle 25 sufficiently to move stop 14a a distance of two needles, as heretofore. While the element 19 is thus raised and the stops have been shifted as just described, transfer of the loops takes place in known manner, after which the element 19 is lowered and the pawl 32 coacts to turn the spindle 26 an additional amount to shift the stops 15a and 16a a distance of one needle.

As indicated in dot-and-dash lines in Fig. 7, the active end of pawl 32 is so formed that 15 it will pass one tooth before engaging ratchet wheel 24 on its downward movement, and consequently only rack said wheel a distance of one tooth.

Of course the mechanism shown and described can be changed and modified in various ways to carry out my novel method of making full fashioned stockings, without departing from the invention herein disclosed and hereinafter claimed.

25 I claim:—

1. In a full fashioned knitting machine, the combination with narrowing rod stops, yarn carrier rod stops, and spindles for actuating said stops; of a reciprocative member; 30 means operable by said member in a single reciprocation thereof for simultaneously operating said spindles to move all said stops and impart a one needle movement to the narrowing rod stops and a two needle movement to the carrier rod stops and for subsequently operating only the narrowing rod spindles to impart an additional one needle movement to the narrowing rod stops.

2. In a full fashioned knitting machine, 40 the combination with narrowing rod stops, yarn carrier rod stops, and spindles for actuating said stops; of a reciprocating member; means operable by said member on movement thereof in one direction for simultaneously operating said spindles to move all said stops and impart a one needle movement to the narrowing rod stops and a two needle movement to the carrier rod stops and operable by said member on movement thereof in 45 the opposite direction for actuating only said narrowing rod spindle to impart an additional one needle movement to said narrowing rod stops.

3. In a full fashioned knitting machine 55 having a carrier rod spindle for actuating yarn carrier rod stops and a narrowing rod spindle for actuating narrowing rod stops; a ratchet on said carrier rod spindle a ratchet 60 on said narrowing rod spindle; individual pawls for operating said ratchets; a reciprocative member operatively connected to and adapted to actuate said pawls on movement of said member in one direction for operating said spindles to impart a two needle move-

ment to said carrier rod and said narrowing rod stops; means associated with the pawl for said narrowing rod spindle to limit the actuation of said narrowing rod stops to a one needle movement while said carrier rod 70 stops are actuated a distance of two needles; and a second pawl associated with the ratchet for said narrowing rod spindle and operable by said reciprocative member on movement in the opposite direction to impart an additional 75 movement of one needle to said narrowing rod stops.

In testimony whereof I affix my signature.
EMIL RICHTER.
